Patented Dec. 11, 1923.

UNITED STATES PATENT OFFICE.

BENJAMIN F. KLEIN, OF CLEVELAND, OHIO.

LIGHTING FIXTURE.

Application filed June 29, 1921. Serial No. 481,219.

To all whom it may concern:

Be it known that I, BENJAMIN F. KLEIN, a citizen of the United States, resident of Cleveland, county of Cuyahoga, and State of Ohio, have invented new and useful Improvements in Lighting Fixtures, of which the following is a specification, the principle of the invention being herein explained and the best mode in which I have contemplated applying that principle, so as to distinguish it from other inventions.

My invention relates to lighting fixtures. Particularly, the invention relates to apparatus of this character utilized for indirect lighting. The object of the invention is to design a fixture of this character which shall be very efficient as regards the effective percentage of the total lumens received; which can be utilized to reflect light in any desired direction; which shall be artistic; which shall be economically manufactured and easily assembled; and which cannot be easily put out of adjustment so as to impair its light efficiency or its appearance.

The annexed drawing and the following description set forth in detail certain means embodying my invention, the disclosed means, however, constituting but one of the various forms in which the principle of the invention may be employed.

In said annexed drawing:

Figure 1 represents an elevation of my improved fixture;

Figure 2 represents an elevation with parts broken away;

Figures 3 and 4 represent, respectively, a fragmentary side elevation and a fragmentary vertical section of an annular reflector rim and ball-chain, forming parts of my invention;

Figure 5 represents a partial elevation and partial vertical section, showing means to which the upper end of the ball chain is secured and also means for locking the ball-chain to position;

Figure 6 represents a fragment of an annular peripheral rim of the upper chain-receiving means; and

Figures 7 and 8 are broken partial elevations and partial vertical sections of different portions of a rigid tubular lamp-supporting and wire-enclosing member, and locking means for the two parts of said tubular member and the shell members associated herewith.

Referring to the annexed drawing in which the several ordinals refer to the same parts in the different figures, the reflector of my improved fixture is denoted by the ordinal 1, the same being suspended by means of the ball-chain 2 from the annular rim 3' of a casing member 3 hereinafter fully described. A tubular two-part lamp-supporting and wire-enclosing member is indicated by the ordinals 4 and 4', the part 4' being suspended by means of its screw-threaded engagement with a wall member, such as a ceiling tripod 5. A ceiling shell is indicated by the ordinal 6 held to position by means of an internally-threaded bushing 7 co-operating with a threaded portion 4² formed upon the lower part of the member 4'. The member 4 also is formed with a threaded portion 4² and the bushing 7 also covers and co-operates with this last-mentioned threaded portion. The bushing 7 is also externally threaded and adapted to co-operate with a nut 9, the latter forming a running collar upon said bushing 7, the externally-threaded part 7' of the latter being of a diameter greater than that of the bushing 7 proper and also greater than that of a lower socket part 7². The collar 9 also gives a pleasing finish to the fixture adjacently below the shell 6. Adapted to be received and accommodated by the socket 7² is an upper of two shell members 8 and 10 disposed respectively, above and below the chain receiving member 3. The latter is in reality one piece with the upper shell member 8 and is a lower enlarged peripheral rim for said shell member and forms upper ball-chain-receiving means. An externally-threaded portion 4³ is secured to the rigid member part 4 and co-operates with a nut 11 having a socket 11' open at the top and adapted to receive and accommodate the shell member 10. The lamp and its associated elements are indicated by the ordinal 12 and the same are, in so far as my invention is concerned, of standard construction.

Referring particularly to Figures 3 and 4, it will be noted that the peripheral rim 13 of the reflector 1 is formed with a downwardly turned bead 14, having a plurality of spaced slots 15 intersecting its lower edge. It will also be noted that the ball-chain 2 is comprised of a plurality of segments 16 spaced by balls 16'. It is evident that any desired segment 16 of the chain 2 may be

slipped up through the slot 15 to suspend the reflector 1 at any desired height. It may be mentioned that, in order to obtain the maximum of lumen efficiency from the lamp 12 or to spot the light from the lamp 12 in any particular place to best fill the requirements of the individual case, the reflector should be correctly hung and this can be accomplished by means of the adjustment 5 10 afforded by the ball-chain 2 and slots 15. In this connection, the size of the lamp 12 affects the height at which the reflector 1 should be suspended.

The member 3 of the upper shell member 15 8 is formed, around a downwardly turned peripheral rim 3', with spaced slots 18 intersecting its lower edge. A segment 16' of the ball-chain 2 can be slipped up into the slot 18 and the rim 3' of the member 3 then 20 snapped over a flange 10' formed upon the shell member 10, as plainly shown in Figure 5. Elements 8 and 10 are held to position by means of the nut 11. In Figure 7 the respective lower and upper ends of the rod 25 parts 4' and 4 are shown as in contact in the plane 4', but the same may be spaced, during assembly, as desired, to obtain the preferred adjustment of the parts, provided, of course, said parts 4 and 4' are both 30 threaded into the bushing 7.

The reflector 1 consists, as plainly shown in Figures 1 and 2, in addition to the rim 13 heretofore described, of a plurality of parabolic integrally connected members 17, each member 17 being the segment of a parabola of different dimensions from that of any parabola of which the other members 17 are segments. This reflector 1 is 35 formed of glass or metal, preferably of spun brass. The same, as well as the shell, supporting, and finishing elements 3, 4, 6, 7, 8, 10 and 11, is finished in white paint 40 enamel.

By means of the rigid tubular member 45 4-4', I am enabled to permanently fix the height of the lamp 12 relatively to the reflector 1. By permanently I mean that the lamp 12, after being put into use, cannot be lifted carelessly or inadvertently so as to 50 impair its adjustment relative to the reflector 1, it being assumed that the fixture has been originally assembled in a careful and calculated manner so as to produce the maximum efficiency. I wish also to particularly point out that my improved construction and assembly of the elements 3 and 10 affords efficient means for locking the ball-

chain to position at the top, which means are also of very pleasing appearance.

What I claim is:

1. A lighting fixture comprising, supporting means; a reflector; a ball-chain for supporting the reflector from the supporting means; means for locking the ball-chain to the supporting means including a downwardly-turned peripheral slotted rim formed upon said supporting means, and a suitably supported shell member formed with a flange over which said rim fastens; and means for supporting a lamp adjacent the reflector. 60 65 70

2. A lighting fixture comprising, supporting means; a reflector; a ball-chain for supporting the reflector from the supporting means, the latter being formed with a rim having peripheral recesses for receiving the chain intermediate any desired two of the balls thereof; means for locking the ball-chain including a suitably supported shell member formed with a flange over which said rim fastens; and means for supporting a lamp adjacent the reflector. 75 80 85

3. A lighting fixture comprising, a wall member; a canopy surrounding the wall member; a depending two-part supporting member, the upper part of which depends 85 from said wall member and extends downwardly below said canopy; a bushing surrounding the adjacent ends of the two supporting member parts and having screw-threaded engagement with said ends, respectively; a running collar engaging the upper part of said bushing, the bottom of said canopy lying adjacently above said bushing and collar; a lamp and a reflector, the lower supporting member part supporting 90 the lamp; and means mounted upon said lower supporting member part supporting the reflector adjacent the lamp. 95

4. A lighting fixture comprising, a wall member; a reflector; a two-part rigid tubular member, one part of which depends 100 from said wall member; a wall shell into which said tubular part extends; means for locking said shell relatively to said part; a lamp, the second tubular part supporting 105 the lamp; a second shell through which said second tubular part passes; means for locking said second shell relatively to said second part; and means for locking said two parts relatively to each other, the reflector 110 being dependently supported from said second shell adjacent the lamp.

Signed by me this 28th day of May, 1921.

BENJAMIN F. KLEIN.
